(57) **CLAIM**

The ornamental design for an auto intake plenum, as shown and described.

DESCRIPTION

FIG. 1 is a top plan view of an auto intake plenum;

FIG. 2 is a bottom plan view thereof;

FIG. 3 is a left side elevational view thereof;

FIG. 4 is a right side elevational view thereof;

FIG. 5 is a front left perspective view thereof;

FIG. 6 is a rear left perspective view thereof;

FIG. 7 is a right rear perspective view thereof;

FIG. 8 is a left front perspective view thereof;

FIG. 9 is a rear elevational view thereof; and,

FIG. 10 is a front elevational view thereof.

A characteristic feature of the design resides in curved roof portion and contoured interior.
